WITNESS:

UNITED STATES PATENT OFFICE.

ANTHONY P. MCCORMICK, OF EAGLEVILLE, PENNSYLVANIA.

STOCK AND DIE OILER.

Application filed November 25, 1922. Serial No. 603,356.

To all whom it may concern:

Be it known that I, ANTHONY P. McCORMICK, a citizen of the United States, residing at Eagleville, in the county of Montgomery and State of Pennsylvania, have invented new and useful Improvements in Stock and Die Oilers, of which the following is a specification.

This invention relates to stock and die 10 oilers and is particularly adapted for the oiling of hand operated devices of this nature. In other words, it is a device for supplying the oil necessary in the cutting of the threads by the stock and die.

One of the principal objects is to provide 15 a device of this nature which shall be simple of construction, easily attached to any standard make of stock and die, and highly efficient for the purpose for which it is designed.

With these and other objects in view as will be more apparent, the invention consists in certain novel construction and combination and arrangement of parts, the essential features of which are hereinafter 25 fully described, are particularly pointed out in the appended claim, and are illustrated in the accompanying drawing, in which:—

Figure 1—is a view of a standard stock 30 and die of the kind in which the dies are internally located, the same being shown as fitted with my improved self-oiler.

Figure 2—is a sectional view of the same.

Figure 3—is a view of another form of die in which the dies are exposed.

Figure 4—is a side elevation of the same 35 party in section for better disclosure.

Like characters of reference refer to like parts in all the views.

Referring to the drawing in detail and 40 particularly to Figure 1, 10 represents the stock of any ordinary and well-known equipment. These stocks are provided as shown with a plate 11 having an aperture or hole 12 where the oil is now introduced by means of a squirt can. The dies are indicated by 45 the reference numeral 13. In applying my device to a stock and die of the type shown

in Figure 1, I simply tap out one of the 50 apertures or holes 12 and insert therein a standard street elbow 14 in the outer end of which is secured an oil cup 15 which may be of any suitable and well-known type provided with an automatically closing vent 16 55 so that as the stock and die are revolved, the oil will not spill out. The elbow 14 is of the type commercially known as a "street" elbow, in other words, an elbow in which the diameter gradually increases from the relatively straight externally threaded portion to the angularly disposed internally threaded outlet. It will be readily understood that the oil will pass from the oil cup 15 through the street elbow 14 and aperture 12 and drop on the pipe or rod being operated upon. 60 65

In the form shown in Figure 2, the plate 11^a which holds the dies 13^a is not provided when it comes from the manufacturer with any aperture. I therefore drill a hole as at 70 75 17 into which I fit a special street elbow 18 having a bottom opening 19, the oil cup 15 may be the same as in the preceding form of the invention. The oil in this case flows from the oil cup into the street elbow 18 and drips from the aperture 19 on to the pipe or rod being operated upon.

While I have described what I deem to be the most desirable embodiment of my invention, I do not limit myself to the specific 80 details of construction or material, nor to anything less than the whole of my invention as defined in the appended claim.

What I claim is:—

The combination with a stock die 85 provided with a threaded recess of a pipe elbow threaded into said recess, so as to form a closure for one end of the elbow, a lubricating cup carried by the elbow at the end remote from the die engaging end, said elbow 90 provided with a relatively small outlet opening in its under surface outwardly of the portion thereof which is seated in said recess.

In testimony whereof I affix my signature.

ANTHONY P. MCCORMICK.
